United States Patent Office

Des. 215,800
Patented Nov. 4, 1969

215,800

FRANKFURTER OR THE LIKE

Edward J. Kiwala, 6338 N. Melvina Ave.,
Chicago, Ill. 60646

Original design application Dec. 21, 1967, Ser. No. 9,878.
Divided and this application Sept. 26, 1968, Ser. No.
15,891

Term of patent 14 years

Int. Cl. D1—04

U.S. Cl. D1—26

Fig. 1

Fig. 2

Fig. 3

Fig. 4

FIGURE 1 is a side elevation of a frankfurter or the like showing my new design, the side opposite thereto being similarly plain and unornamented;

This application is a division of Ser. No. D. 9,878 filed Dec. 21, 1967.

I claim:

The ornamental design for a frankfurter or the like, as shown and described.
